US0D1043409S

(12) **United States Design Patent** (10) Patent No.: **US D1,043,409 S**
(45) Date of Patent: ** Sep. 24, 2024

(54) **ARTICLE OF ADORNMENT**

(71) Applicant: **CARTIER INTERNATIONAL AG**,
Steinhausen (CH)

(72) Inventor: **Irem Oymak**, Paris (FR)

(**) Term: **15 Years**

(21) Appl. No.: **35/518,029**

(22) Filed: **Aug. 8, 2022**

(80) **Hague Agreement Data**

Int. Filing Date: **Aug. 8, 2022**

Int. Reg. No.: **DM/222834**

Int. Reg. Date: **Aug. 8, 2022**

Int. Reg. Pub. Date: **Aug. 11, 2023**

(30) **Foreign Application Priority Data**

Feb. 9, 2022 (WO) WIPO113379

(51) **LOC (14) Cl.** **11-01**

(52) **U.S. Cl.**

USPC **D11/1**

(58) **Field of Classification Search**

USPC D11/1-5

CPC A44C 5/12; A44C 25/001

See application file for complete search history.
